TOY HAND GRENADE

Harry Horowitz and Abraham Schneiderman,
New York, N.Y.

Application April 29, 1958, Serial No. 731,810

4 Claims. (Cl. 46—196)

This invention relates generally to the toy art, and more particularly to a toy hand grenade adapted to simulate grenades in current use by the armed forces of this country.

Actual grenades are designed to incorporate a time fuse which is ignited by percussion cap in turn detonated by a resiliently biased hammer which is released at the time the grenade is thrown. Until such time as the grenade leaves the hand of the thrower, it is held in cocked condition by manual pressure upon a handle which is pressed against the side of the grenade body. When the grenade leaves the hand of the wearer, the hammer pushes aside the handle which is loosely pivoted at one end thereof to permit the hammer to strike the percussion cap which in turn ignites the fuse. After a delay of approximately five seconds, the time fuse has burned through to detonate the charge disposed within the body of the grenade.

The five second period during which time the grenade is usually in flight will normally expire at the time the grenade reaches the ground, so that it will explode before there is an opportunity to throw the grenade back. To have value as a realistic toy, it is desirable that the same simulates the action and operation of an actual grenade.

It is therefore among the principal objects of the present invention to provide a toy grenade simulating both in appearance and operation a conventional grenade of the type in present use by the armed forces.

Another object of the invention lies in the provision of toy grenade construction having means for exploding a conventional toy paper cap either upon leaving the hand of the thrower, or upon contact with the ground after the same has been thrown.

Another object of the invention lies in the provision of a toy grenade of the class described which may be readily reloaded for use many times, thereby materially increasing its value as a toy.

Still another object of the invention lies in the provision of toy construction of the class described in which the cost of fabrication may be of a reasonably low order, with consequent wide sale, distribution and use.

A feature of the invention lies in the fact that many of the parts may be molded of soft unbreakable synthetic resinous material such as polyethylene, polystyrene and the like.

Another feature of the invention lies in the fact that all of the metallic parts may be formed as simple metallic stampings.

Still another feature of the invention lies in the provision of shock absorbing means incorporated in the construction of the device which prevents damage to the firing mechanism upon striking a hard surface.

These objects and features, as well as other incidental ends and advantages, will more fully appear in the disclosure and be pointed out in the appended claims.

On the drawings, to which reference will be made in the specification, similar reference characters have been employed to designate corresponding parts throughout the several views.

Figure 1 is a side elevational view of an embodiment of the invention.

Figure 2 is a vertical central sectional view as seen from the plane 2—2 on Figure 3.

Figure 3 is a plan view of the embodiment showing the safety pin removed.

2

Figure 4 is a fragmentary rear elevational view as seen from the plane 4—4 on Figure 1.

Figure 5 is a view in elevation showing one manner of arming the embodiment prior to the throwing thereof.

Figure 6 is a view in elevation showing an alternate method of firing the embodiment.

Figure 7 is a fragmentary plan view with the handle element removed immediately before firing.

Figure 8 is a similar view after the completion of firing.

In accordance with the invention, the device, generally indicated by reference character 10, comprises broadly: a main body element 11, a cap firing element 12 a handle element 13 and a handle support element 14.

The main body element 11 is preferably molded from suitable synthetic resinous material so as to be relatively light in weight and resistant to breakage. Polyethylene has been found suitable for this purpose. The element 11 includes a simulated charge retaining member 16, a neck member 17, and a cap firing element mounting member 18. The above members are molded integrally, and the mounting member 18 includes an upper planar surface 19, as well as side planar surfaces 20 and 21 which form a seat for the cap firing element 12.

The cap firing element 12 includes a mounting member 24 having a central, generally planar portion 25, a first pair of trunnions 26, a second pair of trunnions 27, a first pair of gripping members 28, a second pair of gripping members 29 and a latch engaging lip 30. In installed condition, the central portion 25 is adapted to lie upon the

upper planar surface 19, the gripping members 28 and 29 being bent to engage small recesses 31 in the side planar surfaces 20 and 21. A spreadable rivet 33 forms a shaft between the first pair of trunnion members 26, while a similar spreadable rivet 34 forms a shaft for the second pair of trunnion members 27. Mounted upon the shaft 34 is a hammer member 35 which is normally urged in a counterclockwise direction as seen in Figure 1 by the action of a spring 36, a first end 37 of which bears upon the central portion 25, and a second end 38 of which engages the hammer member. It will be observed that each of the trunnion members 27 is provided with an elongated cutout portion 39 which cooperates with bent up points 40 to hold a conventional paper percussion cap in position beneath the hammer member 35. The cap, indicated by reference character 41, is pierced by the points 40 so that slippage of the same during the throwing of the device does not occur.

The handle element 13 is also preferably molded from suitable synthetic resinous material, polyethylene being particularly suitable. The overall configuration of the same resembles that of an actual grenade, and includes a rectilinear member 49 as well as a curved member 50 upon which there is disposed an integrally molded latch member 51.

The rectilinear member 49 includes a free end 53 which in the position shown in Figure 1 of the drawing partially overlies the handle support element 14 which is formed of metal to shield the same from direct impact. The second end 54 interconnects with the first end 56 of the curved member 50, the second end 57 of the curved member 50 being positioned to lie adjacent the lower end of the charge retaining member 16. A first bore 58 is disposed as best seen in Figure 2 on the drawing, the same being engageable with a removable safety pin 59, and a second bore 60 provides an axis for pivotal rotation with respect to the handle support element 14.

The handle support element 14 is preferably formed as a metallic stamping, and includes a first pair of trunnion members 62 disposed at a first end thereof and a second pair of trunnion members 63 disposed at a second end thereof. The first pair of trunnion members 62 are provided with bores 64 engageable on the shaft 33, while the

second members 63 are disposed at an angle to support the handle element 13 thereon. An expandable rivet 65 forms a shaft projecting through the bores 65' and the bore 60. A second set of bores 66 align with the bore 58 in the handle element 13, again as best seen in Figure 5.

Referring to the latch member 51 which is preferably integrally formed with the handle element 13, the same projects through an opening 67 in the handle support element 14, so that the reinforced free end 69 is positioned to contact the latch engaging lug 30 as best seen in Figure 1.

The device may be operated either to explode the cap 41 immediately after it has left the hand of the thrower, or may be operated in such manner that it will explode the cap upon striking the ground or other hard surface. Referring to Figures 2 and 5, after withdrawing the pin 59, the handle element 13 may be pressed toward the charge retaining member 16. This causes the same to pivot about the shaft 65 whereby the end of the latch member 51 will clear the lip 30. If the device is thrown in this condition, as soon as the same leaves the hand of the wearer, there will be no means for maintaining the handle support element 14 on top of the hammer member 35 so that it will fly out in a realistic manner as the hammer member rotates clockwise as seen in Figure 1 to detonate the cap 41. (See Figures 7 and 8.)

In the alternative, the device may be thrown after removing the pin without pressing the handle element 13, in which case, as seen in Figure 6 the impact of striking the ground or other hard surface will cause the latch member 51 to be dislodged with the same result.

To reload the device, it is necessary only to bend back the hammer member 35 to a point where the same may be secured by the handle support element, following which the pin 59 is reinserted. Another cap 41 may be positioned upon the points 40 following which the device is again ready for use.

It may thus be seen that we have invented novel and highly useful improvements in toy grenade devices in which there has been provided a harmless realistic replica of an actual grenade as currently used by the armed forces of this country. The device is reusable, and owing to the extensive use of synthetic resinous parts, the same is practically indestructible with continued hard usage. As many of the parts may be made by injection molding or by means of metallic stamping, the cost of fabrication may be of a very low order, and no skill or danger is involved in the reloading of the device which may be locked prior to the insertion of the paper cap.

We wish it to be understood that we do not consider the invention limited to the precise details of structure shown and set forth in this specification, for obvious modifications will occur to those skilled in the art to which the invention relates.

We claim:

1. A cap firing mechanism for use with a toy grenade comprising: a generally planar member having first and second ends, a first pivotal mounting means disposed on said planar member substantially at said first end, a second pivotal mounting means disposed on said planar member between said first and second ends, said second pivotal mounting means including means for supporting a paper cap upon said planar member, a hammer member pivotally supported by said second pivotal mounting means, and resilient means for urging said hammer member in a direction toward said cap supporting means to detonate a cap supported thereby; means connected to said first pivotal mounting means for holding said hammer means against the action of said resilient means in a non-detonating position, said last mentioned means including a second generally planar member having first and second ends, said first end being connected to said first pivotal mounting means, said second end having latching means selectively engageable with said second end of said first planar member.

2. A cap firing mechanism for use with a toy grenade

comprising: a generally planar member having first and second ends, a first pivotal mounting means disposed on said planar member substantially at said first end, a second pivotal mounting means disposed on said planar member between said first and second ends, said second pivotal mounting means including means for supporting a paper cap upon said planar member, a hammer member pivotally supported by said second pivotal mounting means, and resilient means for urging said hammer member in a direction toward said cap supporting means to detonate a cap supported thereby; means connected to said first pivotal mounting means for holding said hammer means against the action of said resilient means in a non-detonating position, and said last mentioned means including a second generally planar member having first and second ends, said first end being connected to said first pivotal mounting means, said second end having third pivotal mounting means thereon, and latching means mounted upon said third pivotal mounting means selectively engageable with said second end of said first planar member.

3. A cap firing mechanism for use with a toy grenade comprising: a generally planar member having first and second ends, a first pivotal mounting means disposed on said planar member substantially at said first end, a second pivotal mounting means disposed on said planar member between said first and second ends, said second pivotal mounting means including means for supporting a paper cap upon said planar member, a hammer member pivotally supported by said second pivotal mounting means, and resilient means for urging said hammer member in a direction toward said cap supporting means to detonate a cap supported thereby; means connected to said first pivotal mounting means for holding said hammer means against the action of said resilient means in a non-detonating position, and said last mentioned means including a second generally planar member having first and second ends, said first end being connected to said first pivotal mounting means, said second end having third pivotal mounting means thereon, and latching means mounted upon said third pivotal mounting means selectively engageable with said second end of said first planar member.

4. A cap firing mechanism for use with a toy grenade comprising: a generally planar member having first and second ends, a first pivotal mounting means disposed on said planar member substantially at said first end, a second pivotal mounting means disposed on said planar member between said first and second ends, said second pivotal mounting means including means for supporting a paper cap upon said planar member, a hammer member pivotally supported by said second pivotal mounting means, and resilient means for urging said hammer member in a direction toward said cap supporting means to detonate a cap supported thereby; means connected to said first pivotal mounting means for holding said hammer means against the action of said resilient means in a non-detonating position, and said last mentioned means including a second generally planar member having first and second ends, said first end being connected to said first pivotal mounting means, said second end having third pivotal mounting means thereon, and latching means mounted upon said third pivotal mounting means selectively engageable with said second end of said first planar member, said latching means including a handle element, a portion of which overlies said second planar member.

5. A cap firing mechanism for use with a toy grenade comprising: a generally planar member having first and second ends, a first pivotal mounting means disposed on said planar member substantially at said first end, a second pivotal mounting means disposed on said planar member between said first and second ends, said second pivotal mounting means including means for supporting a paper cap upon said planar member, a hammer member pivotally supported by said second pivotal mounting means, and resilient means for urging said hammer member in a direction toward said cap supporting means to detonate a cap supported thereby; means connected to said first pivotal mounting means for holding said hammer means against the action of said resilient means in a non-detonating position, and said last mentioned means including a second generally planar member having first and second ends, said first end being connected to said first pivotal mounting means, said second end having third pivotal mounting means thereon, and latching means mounted upon said third pivotal mounting means selectively engageable with said second end of said first planar member, said latching means including a handle element, a portion of which overlies said second planar member, said handle element being formed of flexible material.
